(57) **CLAIM**

The ornamental design for a personalization tag, as shown and described.

DESCRIPTION

FIG. 1 shows a front perspective view of a personalization tag;

FIG. 2 shows a front elevation view of the personalization tag of FIG. 1;

FIG. 3 shows a rear elevation view of the personalization tag of FIG. 2;

FIG. 4 shows a right elevation view of the personalization tag of FIG. 1;

FIG. 5 shows a left elevation view of the personalization tag of FIG. 1;

FIG. 6 shows a top view of the personalization tag of FIG. 1;

FIG. 7 shows a bottom view of the personalization tag of FIG. 1; and,

FIG. 8 shows a front perspective view of a personalization tag of FIG. 1 in an open configuration.

The broken lines in FIGS. 1-8 illustrate the environment of the personalization tag and form no part of the claimed invention.
